INVENTOR
Bryan P Joyce
BY *W. N. Roach.*
ATTORNEY

UNITED STATES PATENT OFFICE.

BRYAN P. JOYCE, OF DAVENPORT, IOWA, ASSIGNOR TO THOMAS A. CONLON, OF SILVER SPRING, MARYLAND.

FLUID-SEPARATING MEANS.

Application filed September 6, 1923. Serial No. 661,372.

(GRANTED UNDER THE ACT OF MARCH 3, 1883; 23 STAT. L. 625.)

The present invention relates to fluid separating means.

The primary object of my invention is the provision of means for separating one fluid from another.

Another object is the provision of means which while normally acting to separate one fluid from another in a cylinder will automatically accommodate itself to changes of pressure in the fluids in said cylinder.

With the foregoing and other objects in view, my invention resides in the novel arrangement and combination of parts and in the details of construction hereinafter described and claimed, it being understood that changes in the precise embodiment of the invention herein disclosed may be made within the scope of what is claimed without departing from the spirit of the invention.

A practical embodiment of my invention is illustrated in the accompanying drawing wherein:

Fig. 1 is a sectional view showing my separating means in place;

Fig. 2 is a section on the line 2-2 of Fig. 1.

Referring to the drawings by numerals of reference:

I have shown at 5 a cylinder provided with the usual packing 6. Reciprocally mounted in this cylinder is a piston or plunger 7.

In the preferred embodiment of my invention the cylinder is formed with an offset as at 8 to provide a pair of chambers 9 and 10 filled with different fluids. Surrounding the piston 7 and seated against the inner walls of the chamber 9 is the separating ring 11 for preventing intermix- 40 ture of the fluids in the two chambers. Attached to this ring 11 as by means of screws 12 is a packing 13 which surrounds the piston and aids the ring in maintaining the fluids in their respective chambers.

In the preferred embodiment of my invention a spiral spring 14 is interposed between the ring and the packing secured thereto and the offset 8 in the cylinder. The separating ring is dished to form angularly directed portions 15 and 16 seating in close contact with the inner walls of the cylinder and the outer periphery of the piston. The

spring 14 serves to maintain the ring in sealing contact with the piston and the inner walls of the cylinder and thereby normally prevent leakage of the fluids from one chamber to another on movement of the piston. Should leakage occur, however, the spring 14 enables the separating ring to adjust itself automatically to the change in pressure in the chamber 9. The chamber 9 is filled, through the valve 17, with a fluid, such as heavy oil or grease, which is supplied under pressure, thereby partially compressing the spring 14, thus assuring an initial pressure on the fluid in such chamber. It is evident then that the pressure on the fluid in the chamber 9 will always be greater than or equal to the pressure of the fluid, air, gas or the like, in the chamber 10, thereby thoroughly packing such chamber against escape of the fluid therefrom past the packing.

While this device will find its greatest use in equilibrators for modern heavy artillery, in the recoil mechanisms for guns, and in devices where high pressure fluids are to be packed and confined, it is not limited to such use but may be used wherever a packing of this character is deemed necessary.

While I have shown a dished separating ring it is obvious that any other suitable type of separating ring may be employed and that for the spiral spring 14 any resilient member or any member which will accommodate itself automatically to changes of pressure may be substituted.

1. claim:

1. In combination, a hollow casing offset intermediate its length to form a plurality of chambers, for the reception of fluids, a plunger reciprocable in said casing, a ring seated in one of said chambers, said ring being dished so as to provide angularly directed portions contacting at their edges with the inner wall of said chamber and the outer wall of said plunger, a packing surrounding said plunger and attached to said ring, said ring and packing normally preventing leakage from one chamber to another and resilient means interposed between said ring and the projections formed by said offset in said casing for maintaining said ring and packing in position, said resilient means permit-

- ting automatic adjustment of said ring and packing to variations in pressure in the chamber in which said ring and packing are seated.
2. In combination, a hollow casing offset intermediate its length to form a plurality of chambers for the reception of fluids, a plunger reciprocable in said casing, a ring seated in one of said chambers and surround-
10 ing said plunger, resilient means interposed between said offset and said ring and normally maintaining said ring in position to prevent leakage from one chamber to another, said resilient means permitting said ring to accommodate itself automatically to variations of pressure in the chamber in which said ring is seated.
3. In combination, a hollow casing offset intermediate its length so as to form a plurality of chambers for the reception of fluids, a plunger reciprocable in said hollow casing, a ring seated in one of said chambers and surrounding said plunger and contacting with the inner wall of said chamber, means interposed between said offset and said ring to maintain said ring in position, said means permitting automatic adjustment of said ring with variations of pressure in the chamber in which said ring is seated.
4. In combination, a hollow casing, provided with a plurality of chambers for the reception of fluids, a plunger reciprocable in said hollow casing, a separating member seated in one of said chambers and surround-
20 25 30
- ing said piston and contacting with the inner wall of said casing, said separating member normally preventing leakage from one chamber to another, spring means for maintaining said separating member in position, said spring means permitting automatic adjustment of said separating member with variations in pressure in the chamber in which said member is seated.
5. In combination, a hollow casing provided with a plurality of chambers for the re-
20 25 30 35 40 45
- ception of fluids, a plunger reciprocable in said casing, a ring seated in one of said chambers and surrounding said plunger and contacting with the inner wall of said chamber to normally prevent leakage from one chamber to another, means for maintaining said ring in position, said means permitting automatic adjustment of said ring to variations in pressure in the chamber in which said ring is seated.
6. In combination, a hollow casing formed with an offset and provided with a plurality of chambers for the reception of fluids, a separating member seated in one of said chambers and normally preventing intermixing of said fluids, and means interposed between said offset and said separating member for maintaining said separating member in position, said means permitting automatic adjustment of said separating member to variations in pressure in the chamber in which said separating member is seated.

BRYAN P. JOYCE.

- ting automatic adjustment of said ring and packing to variations in pressure in the chamber in which said ring and packing are seated. 35
2. In combination, a hollow casing offset intermediate its length to form a plurality of chambers for the reception of fluids, a plunger reciprocable in said casing, a ring seated in one of said chambers and surrounding said plunger, resilient means interposed between said offset and said ring and normally maintaining said ring in position to prevent leakage from one chamber to another, said resilient means permitting said 40 ring to accommodate itself automatically to variations of pressure in the chamber in which said ring is seated. 45
3. In combination, a hollow casing offset intermediate its length so as to form a plurality of chambers for the reception of fluids, a plunger reciprocable in said hollow casing, a ring seated in one of said chambers and surrounding said plunger and contacting with the inner wall of said chamber, means 50 interposed between said offset and said ring to maintain said ring in position, said means permitting automatic adjustment of said ring with variations of pressure in the chamber in which said ring is seated. 55
4. In combination, a hollow casing, provided with a plurality of chambers for the reception of fluids, a plunger reciprocable in said hollow casing, a separating member seated in one of said chambers and surround- 60
- ing said piston and contacting with the inner wall of said casing, said separating member normally preventing leakage from one chamber to another, spring means for maintaining said separating member in position, said spring means permitting automatic adjustment of said separating member with variations in pressure in the chamber in which said member is seated. 65
5. In combination, a hollow casing provided with a plurality of chambers for the reception of fluids, a plunger reciprocable in said casing, a ring seated in one of said chambers and surrounding said plunger and contacting with the inner wall of said chamber to normally prevent leakage from one chamber to another, means for maintaining said ring in position, said means permitting automatic adjustment of said ring to variations in pressure in the chamber in which said ring is seated. 70
6. In combination, a hollow casing formed with an offset and provided with a plurality of chambers for the reception of fluids, a separating member seated in one of said chambers and normally preventing intermixing of said fluids, and means interposed between said offset and said separating member for maintaining said separating member in position, said means permitting automatic adjustment of said separating member to variations in pressure in the chamber in which said separating member is seated. 75

CERTIFICATE OF CORRECTION.

Patent No. 1,593,533.

Granted July 20, 1926, to

BRYAN P. JOYCE.

It is hereby certified that error appears in the printed specification of the above numbered patent requiring correction as follows: Page 1, at the beginning of the specification insert the paragraph:

The invention described herein may be used by the Government, or any of its officers or employees in prosecution of work for the Government, or by any other person in the United States, without payment to me of any royalty thereon, in accordance with the Act of March 3, 1883.;

and that the said Letters Patent should be read with this correction therein that the same may conform to the record of the case in the Patent Office.

Signed and sealed this 10th day of July, A. D. 1928.

M. J. Moore,
Acting Commissioner of Patents.
